INVENTOR
ADELAIDE PARSONS,

*by Bright & Gailey
Atty's.*

UNITED STATES PATENT OFFICE.

ADELAIDE PARSONS, OF CARDIFF, SOUTH WALES.

INITIAL, MOTIF, AND THE LIKE.

Application filed December 30, 1926, Serial No. 158,001, and in Great Britain June 21, 1926.

The object of my invention is to provide an artistic and useful form of initial or other similar representation which can be readily applied by an unskilled person to a handbag or any other article to which it is desired to affix initials, motifs and other representations.

According to this invention, initials, motifs and the like are produced by being stamped or pressed out by means of a die so arranged that the resultant letter or the like has its limbs of arcuate section reinforced by serrations, corrugations or grooves across them to obtain a rigid letter, the hollow back of each letter or the like having an adhesive agent applied thereto whereby the letters and the like are ready for application to bags and other articles by merely moistening or heating the back of the letter to render the adhesive substance sticky.

The face of each letter or the like is preferably coated with a gilt or other suitable colouring agent, and the material from which the letters and the like are made is preferably imitation leather of a fairly rigid nature.

The adhesive agent assists in maintaining the letters rigid and the glue or the like employed preferably fills up the whole of the hollow back of each letter.

The invention as applied to a letter A is illustrated by the accompanying sheet of drawings, in which,

Fig. 1 is a perspective face view,

Fig. 2 is a perspective rear view, and

Fig. 3 is a section on the line *a*—*b* of Fig. 1.

Fig. 4 shows diagrammatically in perspective and enlarged for clearness a suitable form or die, and

Fig. 5 is a transverse section through the two die members on the lines *c*—*d* and *e*—*f*.

Referring to the drawings, a letter according to this invention is shown as consisting of an arcuate section element produced by being pressed out of a strip of imitation leather between a pair of die members 1 and 2 shown in Figs. 4 and 5. One die member has in relief a sharp edge 3 having the outline of the letter to be produced the space bounded by the sharp edge 3 being concave as at 4 to receive a convex relief portion 5 on the other die member. The concave portion 4 and the convex portion 5 have aligning corrugations and recesses 6 and 7 respectively to produce corrugations or ribs 6 in the finished article, which is shown in Figs. 1, 2 and 3. This finished article has a concave section back and a convex section face 8, and the back has applied to it a coating of adhesive material 9 which may if desired fill in the concave surface.

A letter, motif or the like produced according to my invention is of a fairly rigid form so that it does not lose its proper configuration when being applied to an article, and when applied it has the appearance of being pressed out in relief from the surface to which it is applied.

What I claim is:—

An initial, motif or the like for application to hand bags and the like, comprising, in combination, a member of arcuate cross section, the outer face of which is convex and the inner face concave, an adhesive substance within the concave inner face of said member for attaching same to a hand bag or the like, and corrugations formed across said member to reinforce same and to assist in retaining said adhesive substance within the concave inner face thereof.

ADELAIDE PARSONS.
